(57) **CLAIM**

I claim the ornamental design for a tire, as shown and described.

DESCRIPTION

FIG. 1 is a perspective view of a tire, showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is an enlarged view of the claimed area of FIG. 1. The dot-dash broken line represents an unclaimed boundary of the claimed design. The broken lines depicting the remainder of the tire show features that form no part of the claimed design.
